ELECTRICAL SWITCH

Jacques Wppard, New York, N. Y.

Application September 10, 1946, Serial No. 695,887

4 Claims. (Cl. 200--157)

1

This invention relates to an electric switch. The invention will be described in connection with a switch of the type that is adapted for use with household heating pads, heated blankets and the like, but it is to be understood that this particular description is for illustration of the invention only, and does not constitute a limitation.

Electrical hot pads are usually of two kinds, three speed and three heat. The three speed kind reaches a single temperature in each position of the switch, but reaches that temperature at a rate depending upon the contact selected. The three heat type attains a different temperature for each position of the switch. The application of this invention to each type will be described.

It is believed that heretofore all switches generally used on household utensils have had a projecting lever operating a snap switch. The projecting lever catches on things and breaks. It is an object of this invention to make a switch having no projections and no movable lever.

Heretofore, switches have been difficult to assemble and difficult to operate because of size and construction. It is an object of this invention to make a switch that is easy to assemble and dismantle, and easy and safe to operate, in which all electrical parts will be completely shielded and positive in action.

Another object of the invention is to make a switch of attractive appearance as well as superior efficiency.

All switches are subject to pulling at times. The pulling tends to break the switch or to loosen its electrical connections. It is an object of this invention to make a switch that will transmit all pulling stresses to the conductor wires and relieve the connections.

The objects of the invention are attained, generally speaking, by the device described and shown which contains, inter alia, a circular switch element that conceals all contacts, and a body that grips the wires and transfers all stresses to them.

A preferred form of the switch has a body portion that is divided longitudinally in halves, a plurality of terminals mounted in one of the halves, an exterior circular shoulder, spring contacts projecting through the body at the shoulder, and a circular switch element carrying a bus bar for interconnecting the contacts in selected combinations. This preferred form is illustrated in the drawings, wherein:

Fig. 1 is a plan view of the switch.

2

Fig. 2 is a longitudinal section on line 2--2 of Fig. 1;

Fig. 3 is a plan view of one of the half shells with the ring and cap sectioned on line 3--3 of Fig. 2;

Fig. 4 is a section on the line 4--4 of Fig. 2; Fig. 5 is a section on line 5--5 of Fig. 2; Fig. 6 is a detail seen from line 6--6 of Fig. 4; Fig. 7 is a section on line 7--7 of Fig. 2;

10 Figs. 8-12, inclusive, are diagrams of the electrical connections for the three heat pad and the positions of the bus bar and connectors in making the connections; and

15 Figs. 13-17, inclusive, are diagrams of the three speed pad and the positions of the bar and connectors in making the connections.

The first unit of the switch is the casing, which is composed of conforming halves that are separable along a longitudinal plane. The top of 20 one of the halves is seen in Fig. 1 and the interior of the other half is shown in Fig. 3. The terms "upper" and "lower" refer to the positions shown in the drawing.

The upper half, or shell, of the casing is numbered 20, and the lower half is numbered 21. They are provided with flat conforming rims 22, 23 and are held together in assembled relation by a screw 24 that penetrates the shell 20, passes through an interior boss 25 in that shell and is

25 threaded into boss 26 on the interior of the shell 21, and by a cap 27 that is screw threaded onto a screw threaded cylinder projecting from the casing. The cylinder is composed of half cylinders 28 and 29 that form parts of the halves 30 of the casing and bear conforming screw threads.

30 The cylinder and the other end of the casing are of less size than its midpart, and both halves are hollowed out from end to end to provide ample room for the connectors and for making the 35 connections. The problems of assembly in a small space do not need to exist when these principles are followed.

In most switches and plugs any pull upon the wires falls upon the binding posts or soldered 40 connections. This switch provides for the bearing of such loads by the casing. The main hollow part 30 within the casing is entered through openings 31, 32 of reduced size which are formed by rectangular depressions in the halves. Integral, wedge-shaped teeth 33 project from the 45 opposite depressions, approaching each other to a distance sufficient to bite into the insulation that covers the electrical wires or cables that enter the casing. When once assembled, any

50 pull upon the wires is transmitted through the 55

teeth to the casing, relieving the connections of strain.

The cap 27 is provided with an annular abutment 27' that engages the end of the cylinder 28-29 and limits the extent to which the cap may be screwed onto the cylinder. Longitudinal ribs 34, 35 brace the shells and support the bosses 25, 26.

The shells may be molded, carved, cast, or otherwise shaped from plastic materials such as cellulose acetate, phenol-formaldehyde, urea-formaldehyde, and the like, or they may be made from other preferably non-conducting materials. The cost will be affected by the method used. For instance, shells carved by hand from wood would be more costly than shells molded by machine from plastic. The plastic may be homogeneous, mixed with other plastics, fillers, pigments, etc., and it may be supported by a skeleton of fabric, wire, mesh, or the like.

By the employment of three connections and a rotary bus bar, it is possible to operate both a three speed and a three heat pad. The principles employed are illustrated in Figs. 8-17. In Fig. 8, 40 is a typical plug for a lighting circuit, from which an incoming or positive wire 41 extends to a positive or live terminal 42 within the casing. A terminal 43 in the casing is connected through line 44 to a heater element or coil 45 that is in close proximity to a thermostat 46 that controls the flow of current through the entire circuit, and through line 47 to a major resistance or heater unit 48 placed at some distance from a thermostat 49 which also controls the flow of current in the circuit. A terminal 50 in the casing is connected by lead 51 to a resistance 52 and resistance 48. All resistances are connected to the negative prong of the plug 49 by line 53.

A bus bar 91 can be moved into various positions to contact the terminals in various combinations. Thus, in Fig. 9 it connects 43 and 50, but they are not live and consequently this is the off position. In Fig. 10 the bar connects power terminal 42 to terminal 43 and current flows through elements 44, 45, 47, 48, 49, 50, and 53. In Fig. 11 it connects the power terminal to terminals 43 and 50 so that both circuits 51 and 44 are energized. In Fig. 12 only terminal 50 and heater elements 52 and 48 are energized. Thus, there is provided low, medium, and high heat.

To make such connections in the switch a particularly valuable conception is employed. The lower shell 21 has a notched bridge 61, the notch being indicated by number 62 and serving to advance one contact to a position in the arc of a circle with respect to the other two. Screw 63 attaches a spring contact 42 to the notch in the bridge. This contact has a reverse bend 64 and a rounded head 65 made by shaping the end of the contact spring. The outside of the casing has a circular shoulder 66 to the right of an annular step 67 at the base of the screw threaded cylinder 28-29 (Fig. 2). Three grooves 68, 69, 70 are in the shoulder. A hole 71 (Figs. 2, 3, 5) penetrates the wall of the casing, joins the groove 69, and provides the end 65 of the contact 42 with a port through which it may project to a position slightly to the left of the shoulder 66 (Fig. 2).

Similar contacts 43 and 50 are mounted on the bridge and project through the casing into grooves 68 and 70, also projecting above the shoulder 66 and with their rounded contact ends circularly

placed with respect to contact 65. In this position they are capable of being electrically connected to each other in various combinations by a contact bus bar. The positions of these contacts as shown in Fig. 5 may now be compared with the terminals of identical number shown in Figs. 8-17.

The bus bar that is used to connect the several points is a semicircular copper strip mounted on a ring. The ring, 80, is a molded plastic piece having a knurled exterior for gripping, a skirt 81 that encircles the shoulder 66, a shoulder 82 that rests against shoulder 66, and a radial flange 83 with an axial flange 84. The thickness of the ring between shoulder 82 and the top is such that cap 27 holds it in proper position without binding it. Hence, it may be freely turned except as provided by certain notches in the bus bar.

The inner circular edge of the control ring serves as a track upon which the contacts 42, 43, 50 bear. In this track are four notches 85 with bevelled edges 86. Opposite these notches the ring is grooved as at 87 in Figs. 2 and 6. The contact bus bar 90 is a semicircular copper strip having projecting tabs 91, 92, 93 that are bent up into groove 87, and projecting fingers 94, 95, 96 that lie in the grooves 85 and are bent up, over flange 84 (Fig. 3). Tabs 97, 98 project from opposite sides of fingers 94, 95, 96 and lie in the notches 85, in the path of the contacts 42, 43, 50. By turning the control ring the fingers may be made to connect the contacts in particular combinations through the bus bar. The notches combine with the spring contacts to hold the control ring in selected position. These positions may be marked by appropriate signs on the casing and by a pointer 99 on the ring.

The hookup of wires for a three speed control is shown in Figs. 13-17. In those figures a short heater coil is connected to terminal 43, a larger one to terminal 50, and power to terminal 42. The off position is shown in Fig. 14, the energizing of the short heater in Fig. 15, the energizing of both in Fig. 16, and the energizing of the large one only, in Fig. 17.

In assembling the parts the line 53 is passed through the switch without being attached to any of its contacts, and is connected to the negative terminal of the hot pad.

The switch is useful, in various hookups, and with different numbers of contacts, for controlling a great variety of electrical apparatus and circuits. The form disclosed is exemplary, and the two circuits merely illustrative. The switch is very valuable where electrical instruments are to be used in combinations or alone, selectively.

One advantage of the invention is in the construction and operation of the casing and each and every part thereof.

Another advantage of the invention is in the method of assembling the casing and the control ring.

Another advantage is in the electrical connections.

Further advantages have been achieved by attaining the several objects of the invention.

Yet other advantages inhere in the means for relieving connections of strain, in the various contacts taken separately as well as in combination, and in the superiority of a control ring over a lever for controlling electrical circuits.

As many apparently widely different embodiments of the present invention may be made without departing from the spirit and scope

thereof, it is to be understood that the invention is not limited to the specific embodiments thereof except as defined in the appended claims. For example, the prongs 87 may be omitted and a larger or smaller number of contacts, such as contacts 42, 43 and 50, may be employed, two such contacts being useful in a simple "on" and "off" position switch.

What is claimed is:

1. In a switch comprising hollow half shells having conforming edges, hollow interiors, and oppositely disposable depressions with teeth adapted to be set into the insulation of electric wires by assembly of the halves, means to attach contact terminals to the inside of the body, contact terminals attached thereto and having ends projecting to an exterior position in one plane at one end of the body, a ring adapted to be turned to various positions, a bus bar attached to said ring having notched seats adapted to be moved into contact with said contacts, and means to hold the ring over the projecting contacts.

2. A switch comprising hollow half shells having conforming edges, hollow interiors, and oppositely disposable depressions with teeth adapted to be set into the insulation of electric wires by assembly of the halves, means on one half shell to attach contact terminals, three spring contact terminals attached thereto and projecting through holes in the wall of the shell to a position somewhat above an exterior circular shoulder on the body, a ring seated upon the shoulder and adapted to be turned to various positions, a half circular bus bar attached to said ring having notched seats adapted to be moved into contact with said spring contacts, and means to hold the ring in assembled position.

3. A switch comprising hollow half shells having conforming edges, hollow interiors, and oppositely disposable depressions having teeth adapted to be set into the insulation of electric wires by assembly of the halves, means on one half shell to attach contact terminals, three

spring contact terminals attached thereto and projecting through holes in the wall of the shell to a position somewhat above an exterior circular shoulder on the body, a ring seated upon the shoulder and adapted to be turned to various positions, a half circular bus bar attached to said ring having notched seats adapted to be moved into contact with said spring contacts, and a screw threaded cap adapted to hold the ring in assembled position.

4. A switch comprising hollow half shells having conforming edges, hollow interiors, and oppositely disposed holes with teeth adapted to be set into the insulation of electric wires by assembly of the halves, means on one half shell to attach contact terminals, three spring contact terminals attached thereto and projecting through holes in the wall of the shell to a position somewhat above an exterior circular shoulder on the body, a ring seated upon the shoulder and adapted to be turned to various positions, a half circular bus bar attached to said ring having notched seats adapted to be moved into contact with said spring contacts, and a screw threaded cap adapted to hold the ring in assembled position, the ring being adapted to enclose all the electrical contacts.
